UNITED STATES PATENT OFFICE.

CHARLES W. TILLETT, OF FAIRVIEW, OHIO.

FIRE-ESCAPE.

SPECIFICATION forming part of Letters Patent No. 289,730, dated December 4, 1883.

Application filed March 20, 1883. (No model.)

To all whom it may concern:

Be it known that I, CHARLES W. TILLETT, of Fairview, in the county of Guernsey and State of Ohio, have invented certain new and useful Improvements in Fire-Escapes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved fire-escape. Fig. 2 is a longitudinal sectional view of the same, and Fig. 3 is a longitudinal cross-section at right angles to Fig. 2.

Similar letters of reference indicate corresponding parts in all the figures.

20 My invention has relation to so-called "individual" fire-escapes; and it consists in the improved construction of the same, as hereinafter more fully described and claimed.

In the accompanying drawings, A A are the side plates of the device, which are firmly united by bolts B, inserted through connecting-pieces C. In practice I prefer to construct these parts of iron or other suitable metal, to obtain the greatest possible strength 25 with a minimum of bulk, so that the device can readily be carried in a trunk or satchel. The upper parts of the side plates, A A, are recessed, as shown at a, to form bearings or 30 boxes for friction-rollers D, E, F, G, and H, which have a limited play in their boxes a in the side plates, and are arranged in juxtaposition to one another, as shown more clearly in Fig. 2 of the drawings.

15 It is a shaft or drum, which is inserted through bearings i in the enlarged part of the casing composed of the side plates, A, and is provided at its projecting opposite ends with cranks K for turning it. Upon this drum is wound a belt, L, the free end of which is passed between the friction-rollers D E F G H, as shown in the drawings, and is provided with a ring or hook, M, by means of which the free end of the belt may be fastened to the window from 40 which the descent is to be made, or to a suit-

able object inside of the room. At the lower 50 part of the casing is a cross-bar, N, to which a strap, O, may be fastened, and so arranged as to form a seat for the person descending with the escape; or this strap may be arranged to buckle around the body, if desired.

55 In order to regulate the speed at which the belt is wound off the drum in using the device, I provide a brake mechanism consisting of a fixed jaw, P, and a movable jaw, Q, which are arranged at opposite sides of the casing, and 60 also on the opposite projecting ends of shaft I. The swell or eccentric r of the turn-button R, which is pivoted upon a stud or screw, s, projects into a recess, t, in the upper part of the movable brake-jaw Q, so that by turning this 65 button said jaw may be adjusted to bear with greater or lesser force against the free ends of shaft I on opposite sides of its casing. As the free ends of the turn-buttons R can readily be 70 reached and manipulated by the person using the escape, he can at all times regulate the speed of his descent by the escape. This he can also do, if he so desires, by means of the cranks K, which are used for winding up the belt into the device when not in use.

75 Having thus described my invention, I claim and desire to secure by Letters Patent of the United States—

The combination, in an individual fire-escape, of the casing composed of the side plates, 80 A, having recesses a, friction-rollers D, E, F, G, and H, boxed in said recesses, shaft or drum I, having cranks K K, belt L, having a ring, M, or equivalent means for attachment at its free end, a cross-bar, N, adapted to support 85 a strap, O, and a brake mechanism composed of a fixed jaw, P, and a movable jaw, Q, having recesses t and turn-buttons R, the whole constructed and combined to operate substantially in the manner and for the purpose herein shown and set forth.

In testimony that I claim the foregoing as my own I have hereunto affixed my signature in presence of two witnesses.

CHARLES W. TILLETT.

Witnesses:

THOMAS SMITH,
THOMAS BRATTON.
